UNITED STATES PATENT OFFICE

GEORGE LANGFORD, OF JOLIET, ILLINOIS, ASSIGNOR TO MCKENNA PROCESS COMPANY
OF ILLINOIS, OF JOLIET, ILLINOIS, A CORPORATION OF ILLINOIS

RENEWING WORN ANGLE BARS

Application filed March 10, 1928. Serial No. 260,695.

REISSUED

My invention relates to angle bars or fish plates employed in making rail joints, and more particularly to reformed angle bars and the process of reforming or reclaiming worn-out angle bars.

It is known that in use in the track the ends of the joined rails in a joint and the bars connecting said ends wear away due to the rolling of the wheels over the joint. The bearing surfaces, that is, the angular surfaces which are wedged together when the plates are drawn in to the web of the rails, become worn away to a maximum extent on the ends of the rails and the central part of the bars.

It has been proposed heretofore to reform the bars by heating them and reforming them in closed dies, and it is known that in the reforming operation it is desirable to increase the vertical height of the bars along the center so as to make up for the metal worn from the ends of the rails. This is known as crowning the bar. It has heretofore been practiced by holding the bar in such a manner that it could not increase in length, and subjecting it to enormous pressure, thereby forcing metal from the entire length of the bar to flow towards the center and laterally at the center to form the crowns on the bearing surfaces. It has been found in practice that the pressures which are required to do this are enormous for even moderately worn plates, and for badly worn plates the pressure required is so great as to break even the largest commercial presses. I have conceived the possibility of diminishing the thickness of the bar along its neutral axis to supply the necessary metal for filling out the worn part of the bar and for supplying the metal required

to provide the crown. In other words, I apply a spreading pressure at the central part along the neutral axis before closing the dies at the edges. In this way the vertical height along the center third may be increased to produce the necessary crown without resorting to very great pressure in reforming the bar.

It is essential that the distance between the angles of the head and flange bearing surfaces be exact to a predetermined amount,

and that the inside of the head be also as predetermined. The height or distance between the bearing surfaces and the angles thereof determines the fit of the fishing, and the space between the inner side of the bar head and the rail web is the draw or amount of takeup available before the bar is considered worn out. As stated, the fit of fishing and the draw must be precise and only a small departure from precision is tolerated by the users.

Where the wear on the bearing surfaces of the bars is considerable it is obvious that there must be considerable shifting of metal, particularly in a vertical direction, in order that precision in the fit of the renewed or reformed bar may be obtained, and the great difficulty heretofore has resided in forcing the required shifting.

In the practice of my invention I relieve the pressure on the end sections (or thirds of the bar in a short bar) and exert effective pressure on the central portion (or third of the bar in a short bar), producing thereby a renewed or reformed bar thinner than the original bar at the center but higher than the worn bar because of the outward movement of the metal. Such outward movement of the metal may be carried to a point where the height of the bearing surfaces is restored to that of the original bar, or it may be carried to a point beyond the original dimensions to produce the desired crown. I thereby secure a satisfactory reformed or renewed bar with much less expenditure of energy and greater certainty of operation.

Although the strength of the bar produced by my invention is decreased horizontally at the center, it is actually increased in vertical bending strength because of the comparatively great distance of the additional metal from the neutral axis. That is to say, the moment of inertia of the reformed or renewed bar is as great as or greater than the bar as originally manufactured.

In practice I make the greater part of the differences of section, that is, movement of the metal, on the inside of the bar where such differences in section are more permissible than on the outside. The worn center is preferably worked without interference from

the ends, the effect of such working being waves of pressure beginning at the center and moving in all directions therefrom, and the metal flowing in accordance with the 5 waves of pressure.

There are short and long angle bars in use, the former varying from 24 to 28 in. in length, and the latter varying from 36 to 42 in. in length. The greatest stress on the bar is taken 10 up by one-third and by one-fourth the length of the short bars and long bars respectively, the balance being taken up by the end portions.

My invention applies equally to all lengths 15 of bars, but for the purpose of illustration I have shown in the accompanying drawings a short bar.

Now in order to teach those skilled in the art how to practice my invention I have shown 20 in the accompanying drawings for the purposes of illustration the specific embodiment of the invention and the mode of producing the same.

Fig. 1 is an elevational outside view of a 25 standard fish plate or angle bar modified in accordance with my invention.

Fig. 2 is an elevational view of the reverse side or inside of that shown in Fig. 1; and

Fig. 3 is a sectional view taken on the line 30 3—3 of Fig. 1 and showing also the end of one-half of a rail in dotted outline.

Throughout this specification where reference is made to the inside of the bar or plate, it is to be understood as the side normally 35 positioned toward or facing the rail while in use, and the outside refers to the side away from the rail.

The angle bar or fish plate 5, as originally manufactured, is represented by the dotted 40 outline which, in some parts, coincides with the solid outline, representing a section at the center of the reformed angle bar. The ends of the bar receive practically no wear and, consequently, require little or no reforming, 45 but the central portion needs considerable reforming, as heretofore explained.

When necessary, all of the outside surfaces may be modified, but preferably, as shown in Fig. 3, I have confined the greater part of the 50 modification to the inside surfaces. The head crowning is represented by the perpendicular distance between the line *a*—*b* and the line *c*—*d* in Fig. 3, which, in practice, averages about .025 inches, depending on the amount 55 the bar is worn, and this crowning tapers to zero at the ends of the bar, as shown at 5 and 6 in Figs. 1 and 2.

In the preferred practice of the invention 60 where crowning is employed the head surface is raised substantially a uniform height along the central third or fourth of the length of the bar and this rise tapers off to nothing at the ends. That is to say, I do not in practice make a smooth curve as might be 65 inferred from Fig. 1 but rather a flat raised

part at the center and tapered shoulders at the ends.

The flange crowning is represented by the perpendicular distance between the line *e*—*f* and the line *g*—*h* of Fig. 3, which also tapers 70 to zero at 7 and 8. In order that these portions may be crowned, metal is pressed from the sectional area *i*, *j*, *k*, *l*, *m*, *n*, *o* and *p*, shown in Fig. 3, which area tapers to substantially zero at 9 and 10 at the ends of 75 the bar, therefore thinning the web portion 11 approximately $\frac{1}{16}$ th of an inch at the center. Metal may also be shifted from the area *q*, *r*, *s* and *t* of Fig. 3, which, likewise, tapers out at the ends at 12 and 13 as shown 80 in Fig. 1.

The web portion is thinned horizontally and the head and flange portions are crowned vertically, as shown, all at the center and tapering from each end, the moment of inertia remaining substantially the same or increasing, and the weakness resulting at the center is offset by the crowned bearing surfaces. The drawing shows the changes which have been made in exaggerated form in order 90 that they may be perceptible to the eye.

Since the web only of the bar is thinned horizontally, the head and foot portion, or flange, being thinned vertically, the width of the center portion of each of the respective 95 bearing surfaces is not reduced relative to the end portions of such surfaces. When a bar is in use in a joint, the greatest wear occurs at the center portion of the respective bearing surfaces, the end portions of such surfaces being subjected to but slight wear. It becomes important, therefore, to retain 100 the width of the center portion of at least one of the bearing surfaces. This center portion of the bearing surface should be substantially equal in width to the end portions of such surface and, under certain conditions, may advantageously be of greater width than the end portions. While I have illustrated, 105 by way of example, a bar having a relatively wide flange, my invention, in its broader aspects, comprehends bars of various types having a head, a web, and a foot portion which may be in the form of a flange or of other suitable form and width for contact 110 with the rail flange. I also contemplate applying my invention to either one of the bearing surfaces of the bars optionally, or to both of such surfaces.

The dies which I employ are of the character shown in my prior copending application, Serial No. 122,864, filed July 16th, 1926, and I employ the pins or pegs for holding the bolt holes in proper position and to proper size. I find, however, that the severe duty to which these pins or pegs have heretofore been subjected is now very greatly reduced, with the result that the pegs or pins and the dies themselves may be employed for many more operations without wear or in- 120 125 130

jury than has been possible heretofore because of the fact that the end parts of the bars are, according to the present invention, not subjected to the enormous pressure which was heretofore employed in an attempt to secure the necessary metal for filling out the worn central portion of the bar. As above pointed out, the outward movement of metal from the central longitudinal part of the web may be carried to a point where the original height or line of the bearing surfaces is restored to that of the original bar or it may be carried beyond the original line of the bearing surfaces to produce the desired crown. This is capable of certain variations without departing from the spirit of my invention, and I do not intend to be limited by the details herein set forth, but desire to avail myself of such variations as come within the scope of the appended claims.

I claim:

1. A reformed fish plate for rail joints, said plate comprising a head portion, a web portion, and a foot portion, and having a crowned head bearing surface, and the web portion being thinner at the center than at the ends, the center portion of said surface being substantially equal in width to the end portions thereof.
2. An angle bar for rail joints, said bar comprising a head portion, a web portion, and a foot portion, and having a crowned foot portion bearing surface, and a web portion thinner at the center than at the ends, the center portion of said surface being substantially equal in width to the end portions thereof.
3. An angle bar for rail joints, said bar comprising a head portion, a web portion, and a foot portion, and having head and foot portion bearing surfaces, the web portion being thinner and higher at the center than at the ends, the center portions of said surfaces being substantially equal in width to the end portions thereof.
4. A reformed fish plate for rail joints thinner horizontally at the center than at the ends, and higher vertically at the center portion than at the ends, surfaces on said bar tapering from the ends to the center portion.
5. A reformed fish plate comprising head, web and flange portions, convex bearing surfaces on the head and flange portions, the web portion being thinner and higher at the central part than at the ends of the plate, and a surface of said portion tapering from the ends toward the center part.
6. A reformed angle bar for rail joints comprising head, web and flange portions, convex bearing surfaces on said head and flange portions, concave surfaces on said head and flange portions opposite said convex surfaces.
7. A reformed angle bar for rail joints

comprising head, web and flange portions, convex bearing surfaces on said head and flange portions, concave surfaces on said head and flange portions opposite said convex surfaces, one of the surfaces of said web portion being concave.

8. A reformed angle bar for rail joints comprising head, web and flange portions, convex bearing surfaces on said head and flange portions, concave surfaces on said head and flange portions opposite said convex surfaces, the web portion being higher at the center than at the ends, and one of its surfaces having a concavity extending from one end of the bar to the other.

9. A renewed bar comprising a head portion, a web portion, and a foot portion, the web being thinner at the central longitudinal part thereof and the inside of the web being concaved, said bar having a bearing surface the center portion of which is substantially equal in width to the end portions thereof.

10. A renewed bar comprising a head portion, a web portion, and a foot portion, and having angular bearing surfaces restored to be cooperable with new rails and having concavities in the central longitudinal portions of the web and foot portion from which metal has been removed by lateral displacement, the center portions of said surfaces being substantially equal in width to the end portions thereof.

11. An angle bar for rail joints, said bar comprising a head portion, a web portion and a foot portion, and having head and foot portion bearing surfaces and a web portion thinner at the center than at the ends, the center portions of said surfaces being substantially equal in width to the end portions thereof.

12. An angle bar for rail joints, said bar comprising a head portion, a web portion, and a foot portion, and having head and foot portion bearing surfaces and a web portion with the outer surface straight throughout its length and inner surface concave lengthwise of the bar, the center portions of said bearing surfaces being substantially equal in width to the end portions thereof.

13. An angle bar for rail joints, said bar comprising a head portion, a web portion, and a foot portion, and having head and foot portion bearing surfaces and a web portion with one surface concave longitudinally, the center portions of said bearing surfaces being substantially equal in width to the end portions thereof.

14. An angle bar for rail joints, said bar comprising a head portion, a web portion, and a foot portion, said web portion being thinner at the center than at the ends, the bar having a bearing surface the center portion of which is substantially equal in width to the end portions thereof.

15. An angle bar for rail joints with the

web portion higher at the center than at the ends and the head portion thinner vertically at the center than at the ends.

16. An angle bar for rail joints with the web higher at the center than at the ends, and the head and flange portions thinner vertically at the center than at the ends.

17. An angle bar for rail joints, said bar comprising a flange disposed for fishing contact with the rail flange at both the center portion and the end portions of the bar and of less vertical thickness at its central portion than at its ends.

18. An angle bar for rail joints, said bar comprising a flange disposed for fishing contact with the rail flange and tapering in vertical thickness from its ends to its center portion.

19. An angle bar for rail joints, said bar comprising a head and a flange having fishing surfaces for contact with the corresponding fishing surfaces of the rail, the head and flange of the bar tapering in vertical thickness from the ends of the bar to the center portion thereof.

In witness whereof, I hereunto subscribe my name this 29th day of February, 1928.

GEORGE LANGFORD.
